His Attorney.

UNITED STATES PATENT OFFICE

2,229,478

ELECTRIC HEATER

John C. Sharp, Oak Park, Ill., assignor to Edison
General Electric Appliance Company, Chicago,
Ill., a corporation of New York

Application January 28, 1938, Serial No. 187,416

7 Claims. (CL 219—37)

This invention relates to electric heaters, and it has for its object the provision of an improved device of this character, and one which is compact and rugged in its construction, and reliable and efficient in its operation.

This invention relates more specifically to electric heating devices of the hot-plate type such as are commonly used on electric ranges and which support the articles being heated by direct contact. And this invention further contemplates the provision in a device of this character of an improved construction whereby the heating element may be easily and quickly removed from the range and whereby its parts are readily accessible for cleaning when it is removed.

In accordance with this invention, suitable reflector members are provided below the heating element of the unit which are separable from each other, and also from the unit. The reflector members when in their proper operative positions under the heating element form a substantially continuous reflecting surface. The reflector members are further arranged to be supported in their normal operative positions when the heating unit is inserted in its opening in the range by engagement with the supporting flange which usually is provided on the range top around the heating unit openings. The heating unit is further provided with supporting means for the reflectors attached to the heating element and spaced below the reflectors so as to perform no function when the heating unit is in its normal operative position. However, when the heating unit is elevated from the range top opening, it moves the support to engage and hold the reflectors. It is further arranged so that the reflectors can be quickly and easily removed from the support for the purpose of cleaning.

This invention further contemplates improved connector structure for securing supply leads to the terminals of the heater.

For a more complete understanding of this invention, reference should be had to the accompanying drawing in which Fig. 1 is an elevation mainly in section of an electric range hot-plate arranged in accordance with this invention; Fig. 2 is an elevation taken at right angles to Fig. 1 and showing parts in section so as to illustrate certain details of construction; Fig. 3 is a plan view of the heating element in its position shown in Fig. 2, parts being broken away so as to illustrate certain details of construction; Fig. 4 is an enlarged fragmentary view in section illustrating terminal structure arranged in accordance with this invention; Fig. 5 is a bottom plan view of a portion of the heating unit of Figs. 1-4; and Fig. 6 is an enlarged fragmentary elevation of a part of the heating unit.

Referring to the drawing, this invention has been shown in one form as applied to an electric

heating unit intended to be used as the hot-plate of an electric range. The heating unit comprises a pair of heating elements 10 and 11 arranged in spiral form and nested one within the other, as shown in Fig. 3. I prefer to use heating elements of the sheathed type, such as described and claimed in the United States patent to Charles C. Abbott, No. 1,367,341, dated February 1, 1921. Briefly, these heating units comprise a helical resistance conductor 12 mounted in a metallic sheath 13 and supported in spaced relation with reference to the sheath by a layer 14 of electrically insulating and heat conducting material, such as powdered magnesium oxide. The units are supported by means of a framework 15 having roughly the shape of a cross. As shown, the framework 15 comprises a straight transverse portion 15a and two arms 15b extending laterally therefrom. The upper edges of the sections 15a and 15b are provided with spaced notches 16 which receive the heating elements. The heating elements are secured by the upper edges of these notches which flare outwardly toward each other, as clearly shown in Fig. 1. The supporting framework 15 in turn is supported in a ring member 17 which has a circular upright flange 18 to which the end sections of the arms 15 and 15a are directly secured. For this purpose, the flange is provided with vertical slits 19 through which projections or reduced sections 20 on the ends of the arms are inserted. To facilitate the assembly of the support 15 with the flange elongated horizontal slits 21 are provided in the flange at the bottom of the vertical slits 19. The sections 22 of the flange below the slits 21 may then be forced outwardly so as to permit the ends 20 of the support to move freely upwardly into the vertical slits 19, after which the sections 22 are forced inwardly to their positions shown more clearly in Figs. 1 and 3, to securely lock the frame to the ring. The ring 17 further comprises a flat annular ring surface 23 and this terminates in a downwardly extending circular flange 24.

The ring 17 with the heating unit mounted on it is arranged to be inserted in an opening 25 in the range top 26. The range top 26 is provided with a seat defined by an inturned flange 28 and the outer flange 24 of the ring 17 is adapted to be mounted in the seat 28 to support the heating unit within the opening 25. When thus mounted, the annular surface 23 is substantially flush with the range top 26. The support 15 is mounted in the ring 17 so that the upper surfaces of the heating elements 10 and 11 project above the plane of the ring surface 23 whereby utensils and the like may be placed in direct thermal control with the heating elements.

The terminal ends 10a and 11a of the heating elements 10 and 11 extend downwardly at right angles to the plane of the heating elements 60

through the ring flange 18, as shown in Fig. 2. Terminals 28a secured to the ends of the resistance conductors 12 project from these terminal ends of the heating elements, as shown in Fig. 4, 5 and are received in an insulating block 28b constituting a terminal housing, as will be pointed out in greater detail hereinafter.

A pair of semi-circular reflector members 29 are adapted to be positioned under the heating elements 10 and 11, as shown in Fig. 1. Each reflector member has a bottom wall 30 which is of semi-circular form, as shown in Fig. 3. At the outer arc-shaped edge of this surface 30 is an upright semi-circular flange 31 which at its 15 upper edge terminates in an annular ring-shaped flange 32. This flange 32 is arranged to rest on the seat 28 of the range top to support the reflector member in its proper normal operative position shown in the drawing. The two reflector members 29 in these portions cooperate to form a shallow pan under the heating element which pan not only functions as a reflector, but also functions to collect overflow from the cooking utensils, such as water, edibles and the like. 20 Preferably, the bottom wall 30 of each reflector will taper downwardly from the center to the outer edges, as shown, and at these outer edges a plurality of drain openings 33 are provided to permit the overflow to drain from the pan. Also 25 preferably drain channels 33a terminating in these holes will be provided. The channels also form stiffening ribs for the reflectors.

At the chords of the reflectors there are provided a series of arcuate sections 34 which when the two reflectors are positioned together, as shown in Fig. 3, cooperate to define circular openings through which the down-turned terminal portions 10a and 11a of the heating elements pass.

40 Suitable supporting means is provided for engaging and holding the reflector members 29 when the heating unit is elevated from the range opening 25 so as to prevent them from falling away from the unit. This supporting means 45 comprises an elongated member 35 which has roughly an elongated oval shape having lower and upper arms 36 and 37 joined at the center by an upright arm 38. The two lower arms 36 of this member are rigidly secured to the insulating block 28b by means of a bolt 39. The two upper arms 37 are spaced somewhat below the reflector members 29, as shown, and these arms are arranged to support the reflector members when the unit is elevated from its opening. 50 At the center of the unit where the two chord edges of the reflectors meet, the arms 37 and the upright 38 are provided with a notched section 40. The notch 40 is arranged to receive down-turned flanges 41 provided along the chord edges of the reflectors. Thus, when the heating element is elevated, the support 35 secured to it also is raised so that the two upper arms 37 eventually engage the under surface of the bottoms 30 of the reflectors. Under this condition, 55 the down-turned flanges 41 are received in the notch 40 to secure the reflectors to the support 35. The reflectors, therefore, will be carried upwardly with the unit by the arms 37. When the heating unit has been moved upwardly out of the opening, the reflectors may be removed laterally merely by elevating their inner ends to move the flanges 41 out of the notch 40 and withdrawing the reflectors outwardly from the unit. When removed, they may be conveniently 60 cleaned, and thereafter may be reapplied merely 75

by inserting them into their proper positions and dropping the flanges 41 into the notch 40. They will be carried on the support 35 until their other flanges 32 rest on the seat 28. It will be observed that the drain openings 33 are so positioned that drippage flowing through them cannot engage and defile the support 35.

The support 35 is stabilized by means of an arm 41a which is rigidly secured to the down-turned terminal section 11a of the heating element 11, as shown.

Each terminal end of the heater is provided with a cup-shaped terminal housing 42 which has a tapered neck section 43 inserted in the outer end of the metallic sheath 13 of the heater, 15 which preferably also will be tapered, as shown. The housing 42 is secured to the sheath by means of a bushing 44 which surrounds the terminals 28a of the heater element. These terminals are received in apertures 46 provided for 20 them in the terminal housing 28b; and the terminal housing on its upper surface is provided with protuberances 47 around these openings. These protuberances cooperate with the cups 42 25 to prevent the entrance of moisture, dirt, grease and the like into the terminals.

The terminal housing is formed into mating sections 48 and 49, the upper section 48 of which, as shown, bears against the outer edges of the terminal cups 42. The upper housing is provided 30 with a series of chambers 50 to which a series of elongated channels 51 are connected. The channels 51 accommodate the electrical supply leads 52, and the chambers 50 receive suitable connector members 53 which function to connect 35 the leads with the terminals 28a. The connector members have roughly an S-shape and the chambers have a contour similar to that of the connectors. A screw 54 is directed through one of the loops 55 of the connector, as shown, and 40 has its end projecting into the other loop 56. The terminal 28a is clamped between this end of the screw and an arm of the latter loop, as shown. Arranged within the loop 55 is nut 56a which when the screw is turned inwardly to 45 clamp the terminal is threaded outwardly against the opposite arm of the loop. The lead 52, as shown, is secured between the nut and this opposite loop, the parts being so arranged that the lead is securely clamped when the screw is turned 50 inwardly to clamp the terminals 28b.

It will be observed that the two inner terminals 10a and 11a of the two heater elements are electrically connected together by a conducting strip 57 which lies within a channel 58 within 55 the member 48. The chambers 50 and channels 51 and 58 are closed by the lower section 49 of the terminal housing which is secured to the upper section by the bolts 39.

If desired, a grounding lead 60 may be provided in a channel 51, and secured to the screw 39.

While I have shown a particular embodiment of my invention, it will be understood, of course, 65 that I do not wish to be limited thereto since many modifications may be made, and I, therefore, contemplate by the appended claims to cover any such modifications as fall within the true spirit and scope of my invention.

What I claim as new and desire to secure by Letters Patent of the United States is:

1. An electric range heating unit adapted to be inserted in the opening of a range top that has a supporting surface for the unit adjacent the 75

- opening comprising a ring adapted to rest on said surface, a heating element secured to said ring, a plurality of separable reflector members below said heating element cooperating to form a reflecting surface below the heating element, said reflector members having curved flanges adapted to rest on said supporting surface to hold said members in their operative positions under said heating element, a second support spaced below said heating element comprising a plurality of arms attached to said heating element and extending outwardly under said reflecting members respectively so that when said ring is elevated from said surface said arms are elevated to engage and support their respective reflector members, said second support having a notch arranged to receive flanges on said reflector members to prevent them from falling away from said arms when said ring is elevated, and the distance between said second support and said heating element providing for movement of said reflector members upwardly from said notch so that they can be removed laterally from said heating element and ring.
2. An electric heater comprising a heating element, a support on which said heating element rests, a plurality of reflectors resting on said support so as to form a heat reflecting surface below said heating element, a second support having a plurality of arms for said reflectors spaced below them and rigidly attached to said heating element, said second support having a notched section and said reflectors having parts arranged to be received in said notched section to hold said reflectors when said ring is elevated from said first support.
3. An electric heating unit adapted to be inserted in the opening of an electric range top that has a supporting surface comprising a supporting ring adapted to be placed on said supporting surface, a heating element mounted in said ring, a pair of substantially semi-circular reflectors below said heating element constructed and arranged so that their outer edges rest on said supporting surface to hold the reflectors in position under the heating element to form a circular reflecting surface, a support spaced below said heating element and ring attached to said heating element and having a notched section substantially at the center of said circular reflecting surface and a pair of supporting arms directed away in opposite directions from said notched section and inclined downwardly from said section, and said reflectors having down-turned flanges at their chords arranged to be received in said notched section to hold said reflectors to said heating element when said ring is elevated from said supporting surface, the supporting arms being spaced a sufficient distance below said heating element to provide for removal of said reflectors laterally by lifting their flanges from said notched section and laterally withdrawing them in the space between said arms and said heating element and ring.
4. An electric heating unit adapted to be supported in the opening of an electric range top plate that has a supporting seat for said unit comprising a heating element adapted to rest on said seat, a pair of reflectors of semi-circular shape cooperating to define a reflecting surface below said heating element and having flanges at their outer edges adapted to rest on said seat, and also having down-turned flanges at their chords, a support below said reflectors in spaced relation with them, connecting means extending between said support and said heating element rigidly securing them together, and said support having a notch arranged to receive said down-turned flanges to hold said reflectors when said heating element is elevated from said seat, and also having supporting arms for said reflectors.
5. An electric heating unit adapted to be supported on a seat provided for it below the opening of an electric range top plate comprising a ring having an outer edge adapted to rest on said seat, and at its inner edge having a flange, a heating element secured to said flange having terminal portions turned downwardly through said ring, a terminal block secured to the terminal ends below said heating element and ring, a pair of semi-circular reflectors between said heating element and ring and said terminal block and having flanges at their outer edges adapted to rest on said seat, and down-turned flanges at their chords, and a support secured to said terminal block spaced from the reflectors and having a notch arranged to receive said down-turned flanges to hold said reflectors when said ring and heating element are elevated from said seat, and also having a plurality of supporting arms, one for each of said reflectors.
6. An electric heater comprising a supporting ring, a heating element secured to said ring, a pair of reflectors below said heating element cooperating to form a circular reflecting surface and each having as its outer arc-shaped edge an upright flange so that the two reflectors form a pan-shaped container below said heating element, and each reflector tapering downwardly toward its flange and having drain openings near said flange, and also an outwardly extending flange at the top of said upright flange, a common fixed support for said outwardly extending flanges of said reflectors and said ring, and a second support secured to said heating element spaced from the bottom of said reflectors having supporting arms for engaging and supporting them when the heating element and ring are elevated from said fixed support.
7. A range heating unit adapted to be inserted in the opening of a range top that is provided with a supporting surface for said heating unit comprising a heating element adapted to be mounted on said surface, heat-reflecting members separate from said heating element and adapted to be supported by said surface beneath said heating element in a normally operative position so as to constitute a reflecting surface under said heating element which also functions as a bottom wall to collect overflow from said heating element, a normally inoperative support below said reflecting members, means extending between said heating element and support rigidly securing them together so that when said heating element is elevated from said opening said support is carried upwardly with it and when so moved engages and carries said reflecting members upwardly out of said opening so that they may be separated and withdrawn, and said reflecting members having drain openings for said overflow located so that the discharge falling through them does not contact said support.

JOHN C. SHARP.
